UNITED STATES PATENT OFFICE.

JOSEPH H. BLOCH, OF SCRANTON, PENNSYLVANIA.

SHOE-PROTECTOR.

1,124,842.

Specification of Letters Patent.

Patented Jan. 12, 1915.

Application filed July 8, 1910. Serial No. 571,067.

To all whom it may concern:

Be it known that I, JOSEPH H. BLOCH, a citizen of the United States, residing at Scranton, in the county of Lackawanna and State of Pennsylvania, have invented certain new and useful Improvements in Shoe-Protectors; and I do hereby declare the following to be a full, clear, and exact description of the invention, such as will enable others skilled in the art to which it appertains to make and use the same.

This invention relates to improvements in shoe protectors, and particularly to protectors for the heel and sole.

15 The object in view is the arrangement in a shoe protector of a heel member arranged to inclose the heel and have a retaining flange projecting therefrom, said flange and heel member being rigidly secured to the shoe.

With these and other objects in view the invention comprises certain novel constructions, combinations, and arrangement of parts as will be hereinafter more fully described and claimed.

25 In the accompanying drawings: Figure 1 is a side view of a shoe with a heel protector, applied thereto, the same embodying certain features of the invention. Fig. 2 is a perspective view of the heel protector shown in Fig. 1. Fig. 3 is a bottom plan view of the heel protector.

In forming a protector according to the present invention the same is arranged to 35 protect the heel. A housing is provided which substantially incloses the heel and extends upward toward the back part of the shoe to which the device is connected, so as to prevent the accidental removal of the heel from the shoe, and protect the heel from rough usage.

40 Referring to the accompanying drawings by numerals, 9 indicates a housing or enclosure which extends upward any desired distance, and is secured to the upper of the shoe by rivets 10, and secured to the heel of

the shoe by nails passing through suitable apertures in the bottom 11. From bottom 11 the metal extends upwardly at 12 and is bent forwardly and formed into a tongue 50 13 which extends any desired distance toward the toe of the shoe. Tongue 13 is provided with any desired number of apertures 14 through which nails are driven into the shank of the shoe sole for holding the 55 housing 9 in place, and for preventing the knocking off or accidental removal of the heel of the shoe. It will be evident that as long as tongue 13 is in place and not broken off from housing 9 the heel will remain in 60 position.

By the construction and arrangement of protecting means set forth the heel is protected against rough usage and against being knocked off.

65 The various parts of the protector are made from metal in any desired manner, preferably by being stamped from sheet metal. Also preferably the protector is stamped from a single piece of sheet metal 70 so as to obviate any disadvantage of rivets or other securing means.

What I claim is:

A shoe guard comprising a metallic plate provided with a recess adapted to receive the 75 heel of a shoe, the bottom of the recess having nail holes, a counter portion adapted to embrace the counter of the shoe, and having holes around its edge for rivets, said counter portion having a curved upper edge 80 extending downwardly to the front of the heel, and a forwardly extending tapering tongue adapted to bear against the under side of the shank of the shoe and pierced with nail holes.

85 In testimony whereof I affix my signature in presence of two witnesses.

JOSEPH H. BLOCH.
